(57) **CLAIM**

The ornamental design for a golf glove drying aid, as shown and described.

DESCRIPTION

FIG. 1 illustrates a back perspective view of an implementation of a golf glove drying aid.

FIG. 2 illustrates a back view of the golf glove drying aid illustrated in FIG. 1.

FIG. 3 illustrates a front view the golf glove drying aid illustrated in FIG. 1.

FIG. 4 illustrates a side view of the golf glove drying aid illustrated in FIG. 1.

FIG. 5 illustrates a side view of the golf glove drying aid illustrated in FIG. 1.

FIG. 6 illustrates a top view of the golf glove drying aid illustrated in FIG. 1.

FIG. 7 illustrates a bottom view of the golf glove drying aid illustrated in FIG. 1.

FIG. 8 illustrates the front perspective view of the the golf glove drying aid illustrated in FIG. 1.

FIG. 9 illustrates an exploded view of the golf glove drying aid illustrated in FIG. 1 with a fan attachment that fits in a cavity of the front side of the golf glove drying aid.

FIG. 10 illustrates a side perspective view of the golf glove drying aid illustrated in FIG. 9 in which the fan attachment is inserted in the front side of the golf glove drying aid.

FIG. 11 illustrates an exploded view of the golf glove drying aid illustrated in FIG. 1 with a fan attachment that fits in a cavity of the front side of the golf glove drying aid. The fan is inside the attachment and not visible from the front side; and,

FIG. 12 illustrates a side perspective view of the golf glove drying aid illustrated in FIG. 11 in which the fan attachment is inserted in the front side of the golf glove drying aid. The broken line showing of golf glove drying aid is included for the purpose of illustrating portions of the article and forms no part of the claimed design. The dot-dash broken lines define the bounds of the claimed design and form no part thereof. The surface shading lines, when present in the drawings, show contour and/or distinguish between open and solid areas. The Surface shading lines are not surface ornamentation.

1 Claim, 10 Drawing Sheets
